CLAIM

The ornamental design for auxiliary rechargeable battery, as shown and described.

DESCRIPTION

1. Auxiliary rechargeable battery

1.1 : Perspective

1.2 : Front

1.3 : Back

1.4 : Left

1.5 : Right

1.6 : Top

1.7 : Bottom

The gist of the present ornamental design is a combination of shape and pattern of a "auxiliary rechargeable battery" as shown and described.
